UNITED STATES PATENT OFFICE.

FRED EDWARD FANGER, OF MEXICO, MEXICO.

ATTACHMENT FOR TYPEWRITERS.

Application filed April 2, 1920. Serial No. 370,749.

To all whom it may concern:

Be it known that I, FRED EDWARD FANGER, a citizen of the United States, and a resident of Mexico, D. F., Republic of Mexico, have invented a new and Improved Attachment for Typewriters, of which the following is a description.

My invention relates to an attachment for typewriters whereby the user of the typewriter may know at any time and instantly how many lines may still be written upon the unused portion of the paper in the machine.

More especially the invention relates to an attachment for the indicated purpose embodying an indicating element to be revolved with the axle of the platen roller of the typewriter and a relatively fixed indicating element.

The general object of the present invention is to provide an attachment of the indicated character improved in various particulars, more especially with respect to the drive means for the turnable indicating element and the means making provision for the setting of the indicating means, and whereby also to provide an attachment comprising few elements making for simplicity of assemblage and adjustment.

Reference is to be had to the accompanying drawings forming a part of this specification, it being understood that the drawings are merely illustrative of one example of the invention.

Figure 1 is a plan view of a typewriter attachment embodying my present invention illustrating the same applied to the axle of the platen roller shown in part;

Figure 2 is a vertical section through the attachment on the line 2—2, Figure 1, the platen roller being in side elevation;

Figure 3 is a transverse section on the line 3—3, Figure 2;

Figure 4 is a view similar to Figure 2 but illustrating another form of the attachment;

Figure 5 is a cross section on the line 5—5, Figure 4;

Figure 6 is a developed view of the index means on the revoluble indicating element.

Referring more particularly to Figures 1 to 3, A indicates a portion of the usual platen roller of the typewriter; B, the axle thereof; and C, a portion of the typewriter frame. I provide an axle extension 10 formed upon or secured to the axle B to be rigid with the latter for turning therewith,

In the present example, said extension 10 is made tubular at its inner end 11 to receive the end of the axle B and suitably fastened thereto as by set screws 12. For manually turning the extension 10 and the axle B with the platen roller A any suitable means may be provided, such as the usual milled handwheel 13, here shown as fastened by a set screw 14 to the extension 10. Fast on the axle extension 10 is a drive element 15, here shown as a toothed pinion which meshes with and serves to drive pinions 16 turning on stud axles 17 secured to a base plate 18 of suitable form adapted to be secured to the frame C, there being shown for the purpose a flange 19 on said base plate secured by screws 20 to frame C. Rigid with the base plate 18 is an index element in the form of a pointer 21 which extends over a revoluble indicating element 22. Said revoluble element 22 is in the form of a shell presenting an annular flange bearing index means at its outer periphery and includes a plate or disk 23 having a hub 24 fitting the axle extension 10. The revoluble element 22 thus houses the described drive gearing. A clearance is provided at the inner end of the hub 24 to permit it to be moved on the extension 10 toward the drive pinion 15. A coiled spring 25 is provided surrounding the axle extension 10 and the adjacent end of the hub 24, one end of the spring abutting the pinion 15 and the other abutting the plate 23. An internal gear 26 on the indicating element 22 is normally in mesh with pinions 16 to be driven by the latter. The spring 25 normally maintains the internal gear 26 in mesh with the pinions 16 but said spring is yieldable to an inward axial movement of the plate 23 and indicating element 22, so that the internal gear 26 may be moved out of gear with the pinions 16 so that the revoluble indicating element 22 may be turned independently of the axle B and its extension 10 and independently of the gear elements 15 and 16 for optionally setting said revoluble indicating element relatively to the pointer 21.

The indicator element 22 bears on its periphery index means in the form of three annular series of subdivisions and identifying symbols, the divisions and symbols of the respective series being in the ratio to one another of one, two and three, corresponding to single, double and triple spac-

ing of typewritten lines, so that as the platen A is turned forwardly or backwardly the movement is indicated on the element 22 by the pointer 21. In the illustrated example 5 the sub-divisions in one series correspond with single-line spacing and are indicated by numerals in units of six up to seventy-two. The second, intermediate series correspond with double-line spacing and bear 10 numerals in units of three up to thirty-six, while the third series presents sub-divisions corresponding with triple-line spacing and numbered in units of two up to twenty-four.

In practice, the indicating means is set 15 by turning the revoluble element 22 under the pointer 21 after which no further adjustment or manipulation of the attachment is required. The setting as thus stated is done by first disengaging the internal gear 20 26 from the pinions 16, allowing the element 22 to turn freely backwardly or forwardly. The spring 25 automatically returns the plate 23, element 22, and internal gear 26 to a position with the latter in mesh with 25 the pinions 16. It will be obvious that the attachment may be set at any time either before or after placing the paper in the typewriter. The attachment may be embodied in a typewriting machine at the factory or applied to the machine after leaving 30 the factory.

In the form of the invention shown in Figures 4 and 5 an axle extension 10^a is provided, here shown as attachable to or detachable from the axle B of the platen roller A, the tubular inner end 11^a of said extension being secured by set screws 12^a to the axle B, the outer end of said extension having the handwheel 13. Rigid with the extension 10^a to turn therewith is a drive element 15^a here shown as a pinion meshing with a pinion 16^a loose on a stud shaft 17^a projecting from the base plate 18^a, the flange 19^a of which is rigidly secured to the frame 45 C and is provided with a pointer 21 extending over the periphery of the revoluble indicator element 22^a having at its inner end a housing flange 22^b directed radially inward inside of the pinions 15^a, 16^a. The revoluble element 22^a includes a disk or plate 23^a having a hub 24^a sleeved onto the extension 10^a adjacent to the handwheel 13. The stud shaft 17^a has also loose thereon a second

pinion 16^b meshing with a pinion or annular rack 26^a extending about but free from 55 the extension 10^a and secured to plate 23^a by any suitable means such as pins or screws 26^b. An extension spring 25^a is coiled about the extension 10^a between the pinions 15^a, 26^a and abuts respectively at its ends against 60 said pinions to normally maintain the pinion 26^a in mesh with the pinion 16^b to be driven by the latter. Said spring is yieldable to an inward movement of the revoluble indicating element to disengage the pinion 26^a from the pinion 16^b for setting the indicator by turning the revoluble element. 65

I would state in conclusion that while the illustrated example constitutes a practical embodiment of my invention, I do not limit myself strictly to the mechanical details herein illustrated, since manifestly the same can be considerably varied without departure from the spirit of the invention as defined in the appended claims. 70

Having thus described my invention, I claim:

1. A typewriter attachment including a support adapted to be secured to a fixed part of a typewriter adjacent to the axle of the platen roller, an axle extension adapted to be secured to the axle of the typewriter, a pointer on said support, an indicator element revoluble relatively to said pointer and coaxial with said extension, a driven gear 80 element on said revoluble indicating element, a drive element fixed on said axle extension, and a driving connection between said drive and driven element and carried by said support, said revoluble indicating element being optionally turnable independently of 85 said drive element.

2. A typewriter attachment of the class described comprising a rotatable drum, a reducing gear interposed between the said drum and the platen roller of the typewriter which permits rotation of the drum in both directions, index means affixed to the said drum presenting three annular series of sub-divisions corresponding with single, double, 95 and triple spacing and a stationary pointer for simultaneously indicating the corresponding single, double and triple line spaces remaining on the page. 100

FRED EDWARD FANGER.
